CLAIM

The ornamental design for a glove with tomahawk, as shown and described.

DESCRIPTION

FIG. 1 is an elevational view of the backhand side of a glove according to the present invention;

FIG. 2 is an elevational view of the palm side of a glove according to the present invention;

FIG. 3 is an elevational backhand side view of the glove of FIG. 1 being worn by a user according to the present invention; and,

FIG. 4 is an elevational palm side view of the glove of FIG. 2 being worn by a user according to the present invention.

The broken lines showing the glove in use is included for the purpose of illustration and forms no part of the claimed design.
